FOOTBALL GAME BOARD

Preston Waldrop, Dallas, Tex., assignor to Waldrop-Jones, Incorporated, Dallas, Tex.

Application August 7, 1958, Serial No. 52,112

Term of patent 14 years

(Cl. D34—5)

FIG. 2

Fig. 1 is a plan view of a football game board showing my new design; and Fig. 2 is an edge view thereof.

The dominant feature of my design resides in the portion shown in full lines.

I claim:

The ornamental design for a football game board, substantially as shown and described.
